UNITED STATES PATENT OFFICE.

WILLIAM WECKESSER, OF PHILADELPHIA, PENNSYLVANIA.

INSULATED REFLECTOR.

1,248,222.

Specification of Letters Patent. Patented Nov. 27, 1917.

Application filed November 29, 1916. Serial No. 134,057.

To all whom it may concern:

Be it known that I, WILLIAM WECKESSER, a citizen of the United States, residing in Philadelphia, Pennsylvania, have invented an Improved Insulated Reflector, of which the following is a specification.

My invention relates to reflectors for use with incandescent electric lamps; and the object of my invention is to provide a simple, inexpensive and efficient structure particularly adapted for use in connection with the miniature incandescent electric lamps largely employed for Christmas tree ornamentation.

As will be understood, the wiring of Christmas trees is under the jurisdiction of electrical authorities, and such wiring must be passed upon by insurance underwriters. It is necessary therefore to provide a structure that will comply with the rules and at the same time acceptably perform the function for which it has been designed.

My invention therefore comprises a simple form of metal reflector carrying an insulating element by means of which it is secured in proper position with respect to the lamp; the insulating member lying between the plug of the lamp and the socket receiving such plug and completely insulating the lamp and all of its connections from the metal reflector. This structure has been approved by the insurance underwriters.

These and other features of my invention are more fully described hereinafter, reference being had to the accompanying drawings, in which:

Figure 1, is a front elevation of a reflector made in accordance with my invention, and

Fig. 2, is a sectional view illustrating the reflector in its position with respect to a lamp and its socket.

It has long been desirable to equip the small incandescent electric lamps employed for Christmas tree ornamentation with reflectors. The natural color of the tree foliage being dark, the greater portion of the light of the lamp is absorbed. The employment of a reflector therefore materially enhances the brilliancy of the ornamentation and may, in some instances, permit the use of a fewer number of lamps.

In the drawings, 1 represents the reflector, which is preferably of metal and may be of star or other shape, as may be desired, with radial ribs or corrugations 2 to increase the number of reflecting surfaces. This reflec-

tor is slightly dished, as indicated, and is provided with a central recess or socket 3 adapted to receive a disk 4, apertured at 5; said disk being made of paper, parchmentized fiber, rubber, or any other suitable form of insulating material. This disk is held in its seat by displacing small portions of the metal constituting the wall of the socket over the edge of the same, as clearly indicated at 6 in Fig. 2.

A socket of any usual type is illustrated at 7, adapted to receive a lamp 8, having the usual plug 9, and in placing these parts together, the insulating disk 4 of the reflector 70 will lie substantially at the junction of the glass portion of the lamp and the plug, preventing all danger of contact of the metal of the reflector with the plug or socket, and avoiding danger of short-circuiting or other 75 trouble that might cause fire.

These small lamps, when finished, have a drop of solder 10 connecting the leading in wire with the plug adjacent the base of the lamp or where the glass portion joins the 80 plug, and the insulating disk is provided with a small notch 11 to accommodate this drop of solder.

It will be seen therefore that I have provided a simple and efficient form of reflector 85 for small electric lamps, and one that is absolutely safe in use; the disk 4 of insulating material completely insulating the lamp plug from the metal constituting the reflector. At the same time, I have provided a 90 highly satisfactory method of materially enhancing the illuminating value of the lamps employed with Christmas trees, and by having reflectors of different color, the 95 expense of employing lamps of different color is avoided.

I claim:

1. A reflector of metal having an aperture, an apertured insulating disk centrally disposed with respect to the same, and 100 means integral with the reflector and adjacent the aperture thereof for confining the insulating disk thereto.

2. A reflector of metal having a central aperture and an annular recess surrounding 105 said aperture, and an apertured insulating disk centrally disposed with respect to said reflector and confined in the recess thereof by means integral with the reflector and adjacent the recess thereof.

3. A reflector of metal having a central aperture with a recessed flange surrounding 110

the same, and an insulating disk seated in said recess and held in place by upsetting the metal of the reflector.

4. A reflector of metal having a central aperture with a recessed flange surrounding the same, and an apertured insulating disk seated in said recess and held in place by a plurality of prongs upset from the metal of the reflector.

10 5. The combination with a reflector having a centrally located depression with an aperture, of a section of insulating material mounted in said depression, and means integral with the reflector for securing said disk in place; said section of insulating material having a central circular aperture for the passage of an electric lamp plug.

6. The combination with a reflector having a central depression centrally apertured, 20 of an insulating disk mounted in said depression and secured in place therein, said insulating disk having a central aperture for the passage of an electric lamp plug and being notched or recessed at one point of said 25 aperture to accommodate a portion of said plug.

7. A reflector of the class described, comprising, in combination, a light reflecting body, having a central offset seat formed 30 therein, an insulating member positioned within said seat, and tongues integrally formed with said body and being operable

to engage with said insulating disk to retain the latter within said seat.

8. A reflector for electric lights comprising a decorative fancifully shaped body serving as a reflecting medium and having a centrally located opening, and a supporting disk having a bulb-receiving opening formed therein of lesser diameter than the diameter of the opening of said body, said disk being held in a recess surrounding the opening in the reflector by bending a portion of the body.

9. The combination with a socket, an electric lamp having a plug adapted to said socket and a reflector for use with said lamp, of an insulating disk carried by the reflector and apertured for the passage of the plug; said disk being interposed between the socket and lamp and confined in place by the latter and supporting the reflector in proper position with respect to the lamp.

10. The combination with a socket, a lamp having a plug adapted to said socket and a reflector for use with said lamp, of an insulating disk carried by the reflector and apertured for the passage of the plug; said disk being interposed between the socket and lamp and confined in place by the latter and with the reflector separable from said socket and lamp when the latter is removed from the socket.

WILLIAM WECKESER.
